HOOK FOR GARMENT BAG DISPLAY

Daniel E. Gelles, 1140 Broadway,
Kerhonkson, N.Y. 10001

Filed July 12, 1967, Ser. No. 7,783

Term of patent 14 years

(Cl. D54—1)

FIG. 1

FIG. 2

FIG. 3

FIG. 4

FIG. 5

I claim:

The ornamental design for hook for garment bag display, substantially as shown.
